UNITED STATES PATENT OFFICE

GEORGE M. FEUERSTEIN AND CARL FEUERSTEIN, OF ALGOMA, WISCONSIN

BEET HARVESTER

Application filed June 14, 1927. Serial No. 198,803.

This invention relates to beet harvesters, and particularly to the beet topping mechanism thereof.

The general object of the invention is to provide an improved means for trimming the tops off of the beets to thereby clear the way for the topping knife, provide a topping knife, and means for causing the topping knife to raise and lower as it rides over the beets to thus cut the tops therefrom, and to provide means to clear the loose tops from the front of the beet digging plow.

A further object in this connection is to provide a topping knife mounted for vertical movement and an endless belt or equivalent element having its flights extending downward and rearward at an inclination and adapted to ride over the top of the beets, knocking the tops down, and guiding the knife so as to enable the knife to cut off the tops in a uniform manner.

A still further object is to provide means for knocking down the loose tops so that they will not follow around said endless element or belt.

Another object is to provide a device of this character having twin belts or endless elements operatively connected to the topping knife for slight independent movement with relation to the knife to thereby permit these belts to lift independently of each other, making it possible for the endless elements to clear themselves when clogged by dirt or stones.

Other objects will appear in the course of the following description.

Our invention is illustrated in the accompanying drawings, wherein:—

Figure 1 is a fragmentary vertical longitudinal sectional view of the forward end of our beet digger;

Figure 1^a is a vertical sectional view of the rear end of the beet digger;

Figure 2 is a top plan view of the forward end of the beet digger;

Figure 2^a is a top plan view of the rear end of the beet digger;

Figure 3 is a rear elevation of the cutter supporting yoke, the supporting bars thereof being in section.

Referring to these drawings, 10 designates the side bars of the frame. These side bars at their rear ends carry the rear axle 11 upon which are mounted the rear wheels 12. The forward end of the frame is supported upon an axle 13 carrying the steering wheels 14, these wheels being mounted upon steering knuckles 15 and being connected for unitary movement and to be guided by means of the steering wheel 16. We do not wish to be limited to any particular means for steering this beet digger. The beet digger is designed to be drawn by horses through the medium of any suitable tractive hitch. A seat 17 is provided for the operator just rearward of the steering wheel.

Mounted upon a bracket 18 extending forward from the front axle 13 is a sleeve 19 and operating through this sleeve is the vertically disposed pin 20 of a yoke which supports the beet top cutting wheels 21. These wheels are spaced sufficiently apart so that they will extend on each side of the row of beets without touching the beets themselves and will act to cut the loose tops therefrom. These cutting wheels are urged downward by a spring 22 extending around the pin 20 and bearing downward upon the yoke which supports the wheels. The wheels may be raised upward against the action of the spring 22 by means of the operating lever 23 operating over the usual segment 24, the lever being provided with means for engaging the segment and holding the lever in any adjusted position. The lever is disposed, of course, convenient to the driver's seat so that he may have control of these top trimming wheels or disks 21.

Mounted in brackets 25 extending downward from the beams 10 is a yoke 26. This yoke is mounted upon a transverse shaft 27, which in turn is mounted in these brackets, and the yoke is pivotally mounted upon this shaft so that it may be raised or lowered. The yoke carries a lever 28 operating over a segment 29 and engageable with the segment for various adjustments. Extending through the rear end of the yoke is a shaft 30, and mounted upon this shaft and rotating therewith are the forward driving rollers 31 spaced

from each other and supporting the endless belts 32, these belts being disposed side by side and being of any suitable material and of any desired construction. As illustrated, 5 the belts are formed of flat links operatively engaged with each other so as to provide a flexible endless element.

Also mounted upon the shaft 30 for oscillation therearound are the longitudinally 10 extending supporting bars 33 and 34, the bar 34 being longer than the bar 33 and at its rear end being angularly extended, as at 35. The rear ends of the bars 33 and 34 carry bearings 36 within which is disposed the angularly 15 directed shaft 37. Mounted upon the bars 33 and 34 are the two vertical legs 38 of a knife supporting frame, the lower ends of which support the diagonally extending knife blade 39. This supporting frame 38 is connected by a hook 40 to a rod 41 extending 20 upward and pivotally engaged with a lever 42, this lever operating over a segment 43' in the usual manner so that the rear end of the endless elements and the topping knife 25 may be raised or lowered.

Supporting the rear rollers 31^a of the endless elements 32 is a yoke 43 having an upwardly extending spindle 44 which extends through the cross bar of the top of the knife 30 supporting frame. This cross bar has sleeves through which pins 44 extend and yokes 43 are urged downward by springs 45 surrounding the sleeve and pins and bearing against the yokes. Thus, while the rear ends of the 35 endless elements are mounted for movement with the topping knife supporting frame 38, each of the endless elements is independently movable with relation to the other endless element.

40 On the shaft 37 are the approximately conical rollers 46 and 47 having a width of at least that of the corresponding endless elements. These rollers are inclined to the path of travel of the endless elements so as to 45 knock down the loose tops after they have been cut and push them to one side so that they will not follow around with the belts 32. These rollers 46 and 47 are mounted to rotate with shaft 37, and the shaft 37 is driven 50 by a beveled gear wheel 48 meshing with a beveled gear wheel 49 mounted upon a longitudinally extending shaft 50 carrying a beveled gear wheel 51 meshing with the beveled gear wheel 30^a on the shaft 30. This shaft 55 30 in turn carries upon it the pulley 30^b driven by means of a belt or sprocket chain from a pulley 52 mounted on shaft 27. These rollers 46 and 47 are mounted to rotate with shaft 37, and the shaft 37 is driven by a 60 beveled gear wheel 48 meshing with a beveled gear wheel 49 mounted upon a longitudinally extending shaft 50 carrying a beveled gear wheel 51 meshing with the beveled gear wheel 30^a on the shaft 30. This shaft 30 in turn carries upon it the pulley 30^b driven by 65

means of a belt or sprocket chain from a pulley 52 mounted on shaft 27. Shaft 27 carries a sprocket wheel 53 driven by a sprocket chain 54 from a sprocket wheel 55 on transverse shaft 56. This shaft also carries sprocket wheel 57 driven by sprocket chain 58 from sprocket wheel 59 mounted on shaft 11. 70

It will be seen that the forward rollers supporting the endless elements 32 are positively driven from shaft 30 and that the rear rollers for the endless belts are freely rotatable. The conical rollers 46 and 47 are rotated positively in a clockwise direction, forcing the tops onto the ground. 75

Rearward of the beet topping mechanism 80 there is disposed means for cleaning the ground of tops and throwing the tops laterally outward comprising a vertical shaft 60 which carries at its lower end the radiating arms 61 having downwardly extending fingers 62. The shaft 60 is caused to rotate by means of a beveled gear wheel 63 engaged by a beveled gear wheel 64 mounted upon the transverse shaft 56. Operating rearward of the top cleaner fingers are the beet plows 65, 90 and mounted upon the rear end of the frame-bars 10 are the downwardly and rearwardly extending arms or brackets 66. These support the transverse shafts 67 carrying a roller or rollers 68 over which a plurality of belts 95 69 pass. These belts extend forward and over a plurality of rollers 70 mounted upon a shaft 71, which shaft is operatively supported by means of vertically extending rods 72, these rods being connected to a lever 73, which in turn operates over a segment rack 74 whereby the lever may be adjusted and the forward ends of the conveyor raised or lowered. 100

Disposed between the rollers 70 are a plurality of radially pointed or star-shaped disks 75. These are disposed between the several rollers 70 and act to carry the beets up onto the conveyor belts 69 and the conveyor belts carry the beets rearward, shaking the earth off the beets, and discharge the beets rearward 110 of the machine. These conveyor belts 69 are driven by means of a crossed belt 76 which engages a wheel 77 mounted upon the shaft 67 and operating over the wheel 78 mounted upon the traction wheel shaft 11. The beet plows 65 are mounted upon the rear ends of longitudinally extending members 79 supported at their forward ends on vertical members 79^a depending from the beams 10, and are braced therefrom by the braces 80. These longitudinal members 79 are also operatively connected to the cross braces 81 which act to support the rotatable clearer arms 61. These longitudinally extending members are connected by a transverse brace 82, which in turn is connected by a link 83 to a lever 84. This lever is pivotally mounted upon the main frame in any suitable manner and extends rearward over a segment rack 85 with which 120

it may be engaged to hold it in any adjusted position.

For the purpose of kicking the beets upward onto the conveyor 69, we provide a transverse crank shaft 86 which is driven by any suitable means, such as the traction wheels of the machine, this crank shaft having mounted thereon the vertical member 87 having fingers 88 at its lower end. The upper end of this lever 87 is connected by a link 89 to the rear end of the frame of the machine. It is obvious, therefore, that as the crank shaft 86 rotates, the fingers 88 will be caused to describe a circular path and will act to move upward and then downward in front of a beet and then throw the beet upward and onto the conveyor.

The operation of the beet harvester is as follows: The beets are plowed up by the ordinary beet plow or plows suitably mounted on the frame or chassis. Before the beets are plowed up, however, the tops are trimmed by the trimming disks 21 so as to cut off as much of the surplus tops as possible. The topping knife then cuts off the tops of the beets, the topping knife being raised and lowered by the endless elements 32 which, being downwardly and rearwardly inclined, act to climb over the tops of the beets and elevate the topping knife to a proper position to engage the top at its junction with the beet itself. The rear end of this "caterpillar" gauging device, therefore, rides on the tops of the beets, knocking them down, and enabling the knife to cut off the tops in a uniform manner. At the rear of the caterpillar gauging device are the "knock-down" rollers 46 and 47 which tend to keep the tops from traveling over and around the caterpillar belts. Beet tops are very large and tend to clog machines of this character and anything that will pare them down or get them out of the way is a great help to the operation of the machine and to the accurate gauging of the topping knife. These loose tops are further gotten out of the way by the four-armed top clearer which is disposed rearward of the knock-down rollers. This wipes or pushes the loose tops out of the path of the plow so they will not be carried up into the loading conveyor.

It will be seen that the endless belts which act to gauge the topping knife are vertically adjustable at their forward ends by means of the lever 28 which acts to raise or lower the yoke 26 and thus raise or lower the shaft supporting the forward rollers for the endless elements. Thus the inclination of these endless elements may be controlled and the forward end raised or lowered to any desired extent. The rear end of the endless elements and, of course, the topping knife, may be raised entirely out of contact and away from the ground.

It will be seen that this device is relatively simple and it has been found to be particu-

ly efficient in practice, particularly with regard to the means for supporting and lifting the topping knife.

We claim:—

1. In a beet harvesting mechanism, a beet topping knife, a frame supporting the same and mounted for vertical movement, laterally disposed side bars engaged with the frame near their rear ends and extending upward and forward, a shaft upon which the forward ends of the side bars are mounted for vertical swinging movement, rollers operatively supported upon said side bars near the rear ends thereof, a shaft extending through the forward ends of the side bars and pivotally supporting the same, rollers mounted upon the shaft, endless elements, each passing over one of the forward rollers and one of the rear rollers, the endless elements having slight vertical movement at their rear ends with relation to the frame and with relation to each other, and rollers for knocking down the beet tops mounted rearward of said endless elements and upon said side bars, said rollers each having the form of a truncated cone and being mounted upon an axis extending diagonally with relation to the longitudinal movement of the endless elements.

2. In a beet harvester, an inverted U-shaped knife supporting frame, a topping knife mounted at the lower end thereof, side bars having limited movement upon the U-shaped frame and extending forwardly and upwardly from the legs thereof, a transverse shaft upon which the side bars are pivotally mounted for vertical movement, a pair of driving rollers mounted upon the transverse shaft, means whereby said rollers may be driven, roller yokes mounted upon the frame, spring means supporting said yokes from the frame and permitting independent movement of the yokes, rollers mounted upon said yokes, a pair of endless elements passing over the first named rollers and around the second named rollers, one of said elements being longer than the other, a diagonally disposed shaft extending rearward of the endless elements and mounted upon said side bars, and truncated conical rollers mounted upon said diagonal shaft, each behind one of the endless elements and acting to knock down the loose tops as they are cut.

3. In a beet harvesting machine, a beet topping knife, a frame supporting the same for vertical movement, laterally disposed side bars engaged with said frame near their rear ends and pivotally supported at their forward ends whereby said side bars may have vertical swinging movement, rollers operatively supported upon said side bars near the rear ends, rollers operatively supported upon said side bars at their forward ends, endless elements each passing over one of the forward rollers and one of the rear rollers, conical rollers disposed rearward of the

endless elements on an axis inclined to the axes of the rear rollers for said endless elements, and means for rotating said conical rollers in the same direction as the direction of rotation of the rollers supporting said endless elements, said conical rollers acting to knock down the beet tops and shift the beet tops laterally.

4. In a beet harvesting machine, a wheeled supporting frame, a beet topping knife carried by the frame, beet engaging means acting to raise or lower the beet topping knife to bring it in proper relation to the beets, means disposed rearward of said knife and acting to discharge the tops of the beets laterally, and a rotatable top clearer mounted rearward of the topping knife and rotatable in a horizontal plane.

In testimony whereof we hereunto affix our
20 signatures.

CARL FEUERSTEIN.
